UNITED STATES PATENT OFFICE.

WILLIAM E. SELL, OF CANTON, OHIO, ASSIGNOR TO THE SELL HORSE GOODS COMPANY,
OF CANTON, OHIO, A CORPORATION OF OHIO.

GLOVE.

1,102,552.

Specification of Letters Patent.

Patented July 7, 1914.

Application filed January 12, 1914. Serial No. 811,577.

To all whom it may concern:

Be it known that I, WILLIAM E. SELL, a citizen of the United States, residing at Canton, in the county of Stark and State of Ohio, have invented a new and useful Glove, of which the following is a specification.

My invention relates to improvements in gloves and while applicable to many forms of gloves is especially adapted for use on 10 baseball gloves and the like, said gloves sometimes being called mitts, and being usually padded on the palm side of the hand.

The objects of the invention are, to generally improve gloves of the character mentioned, to provide a secure retaining device for holding the glove upon the hand, said device combining strength and durability with neatness and simplicity, and while adapted to retain its proper position, being 20 at the same time flexible and comfortable to the wearer. These objects, together with other objects readily apparent to those skilled in the art, may be attained by the construction illustrated in the accompanying 25 drawings, although the invention may be embodied in other forms, the construction illustrated being chosen by way of example.

In the drawings Figure 1 is a rear view of a baseball glove embodying my invention. 30 Fig. 2 is a sectional view through the glove and wrist pad, taken on the line 2-2 of Fig. 1.

Throughout the several views similar reference numerals indicate similar parts. 35 More specifically describing the construction disclosed in the said drawings, the numeral 1 indicates the palm, the numeral 2 the padding and the numeral 3 the back of the glove proper. The palm 1 and back 3 are arranged to include the said padding between them, the parts of the glove being 40 preferably connected around the edges by the lacing 4 in order that the padding 2 may be removed when desired for the purpose of 45 repair or insertion of new padding. On the back 3 is arranged the hand pocket 5 which may be of any well known construction. Said hand pocket 5 does not extend entirely 50 to the wrist line, but is cut away at 6 leaving the wrist free at the back except for the retaining pad hereinafter described. Extending backwardly and inwardly from the side edges of the glove are the lateral wrist 55 flaps 7 and 8 which extend around the sides of the wrist, the rounded edge 9 extending

across the back 3 at the wrist line, around the rear margins of said flaps 7 and 8 and thence around the margin of the hand pocket 5 to form the edge of the wrist opening. 60

In the use of gloves of the character described it is of importance that the same be firmly held in place at the wrist and that the wrist-engaging retaining device be adjustable for various possible wearers of the 65 glove. To accomplish the proper retention of the glove upon the hand it is important that the wrist flaps 7 and 8 be drawn toward each other in order to closely engage the 70 wrist at the sides and as the said flaps are drawn toward each other it is evident that their inner edges will assume varying positional relations, making it necessary to provide a connecting device for said wrist flaps which will automatically and naturally 75 adjust itself to the varying positions of said flaps. Accordingly, I provide a wrist pad having an inner, soft, flexible, substantial, 80 pad-like lining 10 and an outer back 11, also of flexible material, such as thin leather, but adapted to support the lining 10 and give the same sufficient body to retain its shape. Both the lining 10 and back 11 are 85 preferably of elongated, oval design of a length sufficient to extend somewhat beyond the inner edges 9 of the wrist flaps. The lining 10 extends beneath the wrist flap 8 while the back 11 extends above said flap. Intermediate the ends of the back 11 the 90 strap aperture 12 is provided through which a strap 13, preferably somewhat longer than the wrist pad extends. The portion of the strap 13 on the inner side of the back 11 extends to and over the outer side of the flap 8, lying between said flap and the back 95 11, as clearly illustrated in Fig. 2. Stitching 14 extends through the back 11, strap 13, flap 8 and lining 10 fixedly connecting said parts with relation to each other. Said stitching also extends around the margins 100 of the back 11 and lining 10 to connect the same. Adjacent the aperture 12 stitching 15 is also employed to connect the back 11, strap 13 and lining 10. From the aperture 12 the free end of the strap 13 extends 105 transversely toward and beyond the free end of the wrist pad and is provided with buckle apertures 16.

Upon the outside of the wrist flap 7 is connected a buckle 17, which is preferably 110

set sufficiently back from the edge 9 so as to prevent said buckle from having a tendency to bear toward the wrist of the wearer beyond the edge 9 of the flap 7. The free end 5 of the strap 13 is adapted to be connected to said buckle on the outside of the flap 7, while the free end of the wrist pad, including both the lining 10 and back 11 extends beneath said flap 7, as more clearly illustrated in Fig. 2.

It will be noted that the wrist pad being fixedly connected at one end to the flap 8 will be substantially free to assume slightly varying angular positions with reference to the flap 7 in accordance with the various adjustments of the strap 13 and buckle 17, being sufficiently supported and held in place, however, by the connection of the strap 13 with said wrist pad intermediate the ends 20 thereof. It will also be noted that the lining 10 constituting, as hereinbefore described, a substantial pad-like member, extends under the edges of both of the wrist flaps, and that beneath the wrist flap 7, on which the buckle 17 is arranged, the wrist pad, including the back 11 extends, thus giving added protection beneath that portion of the flap 7 most likely to produce chafing or other injury to the wrist. It should be further especially noted that the wrist pad is adapted to serve almost exclusively as a pad, the strain of connection between the flaps 7 and 8 being carried almost entirely by the strap 13 which, it will be noted, extends entirely 35 from one wrist flap to the other.

In use, when the strap 13 is drawn up to retain the glove upon the hand the pad-like lining 10 will extend entirely across the back of the wrist from side to side, giving a 40 smooth, continuous surface adapted to engage the wrist in the various, rapid and energetic movements of the wearer without impeding such movements or producing a

chafed or otherwise uncomfortable condition.

Although the drawings and the above specification disclose the best mode in which I have contemplated embodying my invention, I desire to be not limited to the details of such disclosure, for many changes in form 50 and construction may be made as circumstances require or experience suggests without departing from the spirit of the invention within the scope of the appended claim.

I claim:—

In a glove provided with a hand pocket having a cut-away portion providing a back wrist opening and lateral wrist flaps at the sides of said opening, means for retaining the glove on the hand, comprising a wrist 60 pad, a buckle and a strap, said wrist pad comprising an inner, soft, flexible lining member and an outer back member, both of a length adapted to extend beyond the inner edges of said wrist flaps, said lining and 65 said outer back member fixedly connected to and including between them one of said lateral wrist flaps, said strap extending through an aperture in said outer back member intermediate the ends thereof and 70 having one end fastened to one of said lateral wrist flaps, under said outer back member, said buckle connected to the other lateral wrist flap upon the outer side thereof, the free end of said strap adapted for connection to said buckle, and the free end of 75 said wrist pad, including the lining member and back member, extending beneath one of said lateral wrist flaps.

In testimony that I claim the above, I 80 have hereunto subscribed my name in the presence of two witnesses.

WILLIAM E. SELL.
